Kerrick G. Odde

UNITED STATES PATENT OFFICE.

CLAYTON M. BOUDETTE, OF REVERE, MASSACHUSETTS.

SOUND-REPRODUCING APPARATUS.

Application filed August 4, 1923. Serial No. 655,779.

This invention relates to sound reproducing apparatus and is especially concerned with the problems presented in the volume reproduction of sounds transmitted by radio telephony.

In radio work it is now a common practice to use so-called "loud speakers" in reproducing music, speeches and the like. While these pieces of apparatus give very satisfactory reproductions under some conditions, they produce very distorted results at other times and they give only very faint and scarcely audible reproductions under many circumstances.

It is the chief object of the present invention to devise a loud speaking apparatus which will reproduce music, speech, or other sounds truthfully, preserving the original quality and tone.

In devices of this character a receiving diaphragm is caused to vibrate in accordance with or respond to the pulsations or movements of a transmission device connected thereto, and the present invention relates to a novel connection between the diaphragm and said device for vibrating it, that substantially eliminates the distortions produced in prior sound reproducing instruments, whether operated mechanically or electrically, due to the natural frequency period of the diaphragm.

The invention is illustrated, for the purpose of explanation, as applied to an electro-magnetic diaphragm vibrating mechanism, is especially designed to utilize the weak fluctuating "voice currents" of wireless receiving apparatus in a manner which enables these currents to produce finer gradations in the vibrations of the receiving diaphragm, as disclosed in my Letters Patent of the United States No. 1,557,554 dated Oct. 20, 1925 for sound reproducing apparatus, of which this present application is a division.

While the invention is illustrated and described in connection with loud speaking apparatus designed for use in radio telephony, it can also be used to advantage in other sound reproducing apparatus, whether operated electro-mechanically or mechanically.

The nature of the invention will be readily understood from the following description when read in connection with the accompanying drawings, and the novel fea-

tures will be particularly pointed out in the appended claim.

In the accompanying drawings, showing the preferred form of the invention,

Figure 1 is a view, partly in side elevation and partly in vertical cross section, showing a diaphragm connected, in the novel manner hereinafter described, to the electro-magnetic diaphragm vibrating apparatus described in my co-pending application hereinbefore referred to; and

Fig. 2 is a view, in plan, of the same diaphragm and diaphragm vibrating apparatus as shown in Fig. 1, with the horn holding plate removed.

Only a brief description will be given of the illustrated diaphragm vibrating apparatus since a full disclosure of its construction and function will be found in said parent Patent No. 1,557,554, to which reference may be had.

The construction illustrated comprises four permanent magnets 1, 2, 3, 4 of the horse-shoe type arranged with their poles adjacent, magnets 1 and 3 being superposed on magnets 2 and 4. The magnets are properly spaced by suitably arranged lugs 6 on a non-magnetic supporting frame 5 and the whole is clamped to a non-magnetic base plate 9 by screws 7-7 having collars 8-8 that bear on the upper edges of the magnets 1 and 3.

Mounted between the poles of the permanent magnets is an armature 12, comprising preferably a thin plate of silicon steel, pivoted at its ends 13 in metal yoke pieces 14-14 secured to the frame 5, and provided at one corner with a lug 15 which projects beyond the lateral faces of the magnets 3 and 4. This lug 15 is connected by means of a rod or other suitable transmission device 16 with the central portion of a resilient diaphragm 17. The marginal portion of this diaphragm is clamped with even marginal pressure, as usual, between two rubber rings 18-18 located in an annular recess formed in the lower part of the base plate 9, the rings being held in this recess by a plate 19 secured to the base 9 by screws 20-20. The diaphragm preferably is made of mica, and the supporting means just described leaves the circular central area of this diaphragm free to vibrate, as usual in apparatus of this type. The plate 19 is pro-

100
105

vided with a hollow nipple 23 located opposite the central portion of the diaphragm 17, to which nipple a horn or equivalent device may be connected.

5 While the armature 12 may oscillate about its pivotal connection to the yoke pieces 14-14, its connection to the resilient diaphragm 17 holds it normally in a neutral or central position. The armature 12 is oscillated about its axis by means of a coil 25 which encircles it, with the plane of the windings lying at right angles to the axis of the armature. The effect upon the armature when the fluctuating voice currents flow 10 through the coil need not be detailed here in view of the full description in said co-pending application, it being sufficient to remark that the tipping of the armature in a clockwise or counterclockwise direction 15 (viewing Fig. 1) is controlled by the direction of flow of the current through the coil. The force of the tipping movement will, of course, vary with the intensity of the current flowing through the coil, but very 20 feeble currents will produce relative powerful oscillations of the armature.

These oscillations will be positively transmitted to the diaphragm 17 through the transmission rod 16, thus producing in the 30 diaphragm vibrations varying with the fluctuations of the current in the coil 25.

In using an evenly clamped circular diaphragm to reproduce the sound waves, as is the practice in most sound reproducing instruments, there is a tendency to accentuate 35 or emphasize those sounds having a frequency which agrees with the natural frequency period of the diaphragm. This is very largely responsible for the distortion produced in the present loud speakers.

I have discovered a means for substantially eliminating the distortions produced in prior sound reproducing instruments due to the natural frequency period of the diaphragm. In these prior instruments the connection from the transmission mechanism to the diaphragm is generally made at the 45 geometrical center of the diaphragm. I have found that by decentering this connection without stiffening a considerable area of the diaphragm the natural frequency period of the diaphragm appears to be substantially destroyed and that a very marked increase in clearness of tone and faithfulness 50 of reproduction is effected. This sensitiveness to tonal values is obtained because the decentering of the vibrating arm connection prevents the diaphragm from reproducing or accentuating frequencies of a 55 particular period to which the diaphragm would otherwise respond. This decentering need not be great; for instance, in a two inch diaphragm a decentering of one-sixteenth of an inch produces very satisfactory 60 results.

The preferred construction is illustrated by the drawings, both figures showing the transmission rod 16 connected to the diaphragm 17 off-center, that is, the connection is not exactly to the geometrical center of 70 the area of the diaphragm within the peripheral clamping rings 18. To indicate this clearly, the geometrical center of the diaphragm area having a natural frequency period is indicated on Fig. 1 by the arrow 75 22, and on Fig. 2 by the center-cross 22. It will be observed that this point does not coincide with the point of connection of the rod 16 but that the latter point is at one side of it, that is, the rod connection is de-centered. The diaphragm end of the rod 16 is connected directly to the diaphragm by being entered in a hole, made for its reception at the desired off-center point, and then clamped to the diaphragm in any usual 80 or convenient manner that provides for a normal projection of the clamped end from the diaphragm. In the present instance a normal projection of the rod 16 is obtained by providing it with a shoulder near its 85 end, the face of which is in a plane normal to the axis of the rod. The rod end beyond this shoulder, that projects through a hole in the diaphragm, receives a threaded nut by which the diaphragm is clamped against 90 said shoulder, all as clearly shown at 24 in Fig. 1.

This feature of the invention can be used to advantage not only in receivers of reproducers which are operated electro-magnetically, but also in those which are operated mechanically. While the transmission rod 16 is illustrated as a straight bar connecting the diaphragm and armature, those skilled in the art will understand that it is within the scope of the invention to use a bent rod 105 when the construction of the apparatus in which the diaphragm is to be used is such as to require it. When either a bent or a straight transmission rod 16 is used, the spot-connection to the diaphragm formed by the rod clamp 24 is such that the portion of the 110 vibration area stiffened by the rod clamp is so small as to cause no restriction to the natural responsive movement of the diaphragm. The relative size of the spot-connection, in the illustrated form, may be visualized by comparing the area of the diaphragm 17 with that of the rod clamp 24, 115 in Fig. 2. It will be observed that the illustrated transmission connection leaves the diaphragm wholly unrestrained except for its marginal clamp, that is, the free or natural response of the diaphragm to all frequencies, i. e. to all impulses given to the 120 transmission rod, is not restricted by increasing the stiffness coefficient. This is highly important in reproducing or regenerating signals by means of the weak current from a radio broadcast receiver. Perfection in 125 130

reproduction is possible only when the reproducing instrument is so sensitive as to enable it to respond accurately to all impulses, regardless of the frequency, generated at the armature end of the transmission rod. This means an elimination, so far as mechanically possible, of all the reactive forces that tend to distort the signals due to the direct magnetic pull.

10 For the most perfect reproduction the diaphragm of the present invention is formed of material having an even thickness, or a uniform sensitivity to vibration throughout its area within the clamping rings 18. The 15 off-center, spot-connection of the transmission rod produces an infinite number of lines or vibration loops of equal sensitivity, each one differing in length from all the others. Consequently the diaphragm has no specific 20 or natural frequency period and, because it will not unduly respond to or accentuate some particular frequency but yet does respond freely to extremely weak impulses, distortion of sound caused by these defects 25 in prior instruments is eliminated.

From the foregoing it will be understood why the configuration of the transmission rod connection must be in the form of a small spot, rather than in the form of an elongated 30 slit or slot, which would cause the stiffening of such a large circular area as to prevent the diaphragm from responding in the manner just described.

I have found in actual practice that this

apparatus reproduces music, speech, and the 35 like, transmitted by radio, clearly and faithfully and is far superior to prior forms of apparatus of this character of which I have been able to learn. The difference is particularly marked where a volume reproduction 40 of the transmitted sounds is made.

It will be clear to those skilled in the art to which this class of apparatus pertains, and with the general objects of the present invention in view, that changes may be made 45 in the details of structure, the described and illustrated embodiment thereof being intended as an exploitation of its underlying essentials, the features whereof are definitely stated in their true scope in the claim here- 50 with.

Having thus described my invention, what I desire to claim as new is:

In a sound reproducing apparatus, the combination of a circular diaphragm formed 55 of material of a uniform thickness throughout having a hole therethrough located to one side of its geometrical center, a transmission rod mounted at one side of the diaphragm having one end projecting through 60 said hole, means for securing the rod in said hole by clamping pressure that stiffens only an extremely small spot on the surface of the diaphragm, and means for clamping the diaphragm at its periphery in a manner to 65 provide a circular vibration area the center of which is at said geometrical center.

CLAYTON M. BOUDETTE.
